UNITED STATES PATENT OFFICE.

ERASTUS WOODWARD, OF SOMERVILLE, MASSACHUSETTS.

HEEL-ATTACHING MACHINE.

No. 844,573.

Specification of Letters Patent.

Patented Feb. 19, 1907.

Application filed January 28, 1903. Serial No. 140,833.

To all whom it may concern:

Be it known that I, ERASTUS WOODWARD, of Somerville, in the county of Middlesex and State of Massachusetts, have invented 5 certain new and useful Improvements in Heel-Attaching Machines, of which the following is a specification.

My invention relates to a machine for attaching heels loaded with nails to the heel-seats of boots and shoes, and where blind-nailing is employed to the subsequent attachment of top lifts to the attached heels.

My improvement is shown applied to a heel-ing-machine in which there is a vertically-reciprocating cross-head carrying a hub adapted to be oscillated about a shaft and provided with two diametrically-arranged arms, one of which carries the nail-driving mechanism to which the loaded heel 15 is applied for attachment to the shoe and the other arm being adapted to subsequently attach or spank the top lift onto the attached heel at the proper time. I have not shown in the drawings the mechanism for reciprocating this cross-head, as it is too well known in the art to require description.

My invention consists of certain novel features hereinafter described, and particularly pointed out in the claims.

30 In the accompanying drawings, which illustrate a construction embodying my invention, Figure 1 shows a side elevation of the cross-head referred to, together with the jack in position thereunder for holding the shoe, and also showing the loaded heel held 35 on the upper arm, to which it has been applied by the body. Fig. 2 is a similar view with the arms reversed and showing the heel above the jack in position to be attached to 40 the heel-seat of the boot or shoe. Fig. 3 is a top plan view of Fig. 2 and showing the top-lift-carrying device out of the vertical line of motion of the arm carrying the heel during 45 its attachment to the heel-seat of the boot or shoe. Fig. 4 is a side elevation showing the cross-head down with the heel attached to the shoe. Fig. 5 is a side elevation similar to Fig. 4 with the arms reversed and showing the projecting ends of the nails onto which 50 the top lift is to be attached. Fig. 6 is a view similar to Fig. 5 with the cross-head down and the spanker-block attaching the top lift to the projecting ends of the nails. Fig. 7 is a view similar to Fig. 6, showing the

cross-head raised with the arms and the heel 55 finished. Fig. 8 is a top plan view of the top-lift-carrying device in the position shown in Fig. 1 when the heel is applied by the boy to the arm carrying the heel-attaching mechanism. Fig. 9 is a top plan detail view of 60 the top-lift-carrying device with the parts in the position shown in Fig. 2 out of the driving-line of the arm carrying the heel. Fig. 10 shows a top lift applied to the top-lift-carrying device and ready to be moved into position under the spanker-block for attachment to the attached heel. Fig. 11 is a top plan view of the top-lift-carrying device and in the driving-line of the spanker-arm for attachment of the top lift to the attached heel. 65 Fig. 12 is a cross-sectional view through the cross-head on the line *a a*, Fig. 1. Fig. 13 is a cross-sectional view through the head and hub with the two arms in full lines on line *1 1*, Fig. 2. Figs. 14 and 15 are respectively 70 side and under side plan views of the mechanism which operates the top-lift-carrying device, representing the parts in their positions when the top-lift-carrying device is out in position to receive a top lift. Figs. 16 75 and 17 represent, respectively, side and under side plan views of the mechanism which operates the top-lift-carrying device, showing the parts in their positions when the top-lift-carrying device is moved inward with the 80 top lift over the heel for attachment thereto.

Like letters of reference refer to like parts throughout the several views.

In the drawings the cross-head *A* is reciprocated, by means of the rods *A'*, in the manner well known in the art.

*A*² is the last, carrying the shoe to which the heel and top lift are to be attached when blind-nailing is employed and to which the heel only is to be attached when flush-nailing 95 is employed. The hub *B*, attached fast to the shaft *B'*, which is set at an angle of thirty degrees, carries the diametrically-arranged arms or blocks *B*² *B*³, and said hub and arms are adapted to be firmly held in position during the attaching operation by the arm *C*, pivoted at *C'* on the cross-head *A* and normally caused to engage a suitable recess in each arm by means of the spring *C*². (Shown in Figs. 1, 2, and 3.) Secured fast to the lower end of the shaft *B'* is the arm *D*, to which is pivotally connected at *D'* the lever *D*², which at its opposite end is pivotally con-

nected to the arm E by the pin D³, extending down through the opening in the movable arm E, mounted freely on the sleeve e' around the rod E', which extends upward from the base of the machine. The end of this arm E opposite the lever D² is supported in the lugs e, secured to and extending from under the cross-head A, and in the movements of the lever D² the arm E moves to and fro on the sleeve e', supported in the lugs e. From the under side of the arm E there extends downwardly the depending rod E², which passes through the slot E³ in the bifurcated arm E⁴, held fast on the rod E' by the set-screw E⁵. Secured to the boss E⁶ on the arm E⁴ is the plate E⁷, to which are pivotally secured two links E⁸ E⁹ at F and F'. The forward end of the link E⁸ is pivotally connected at F² to the arm F³ of the link F⁴, to which is secured the forward end of the link E⁹ at F⁵, forming the well-known parallel motion. The spring F⁶, secured to the link E⁸ at one end and at its opposite end to the pin F⁷, tends to hold the forward end of the arm F³ in a parallel closed position with respect to the forward end of the plate E⁷ and exerts a pressure on the top lift to hold it square and clamped in a suspended position as it travels into position over the attached heel. On the forward end of the plate E⁷ are two guides G G', in which there is adapted to slide the forked plate G², having shoulders, as shown, to limit the forward movement of said plate under tension of the spring G³, secured to the plate E⁷ and to the pin G⁴. The top lift is placed on the top-lift-carrying device by putting its breast against the parallel arm F³ and forcing said arm out until the top lift Y drops into the fork in the plate G², which yields as the arm F³ returns to its normal position under the tension of the spring F⁶ until the back of the top lift strikes the edge of the forward end of the plate E⁷, which is the gaging-point of the top lift, the plate H preventing the top lift falling through during its application, as above described. The plate H is located on a suitable standard extending up from the base of the machine and is fixed in positive relation to the arm F³ and the forward end of the plate E⁷, so that when the top-lift-carrying device is moved out into position to receive a top lift it comes directly over the plate H in close proximity thereto and prevents the top lift when being applied thereto from passing through. The machine is so organized that when the top lift is arranged as described and brought over the attached heel its rear end comes over the rear end of the heel in a positive relation to the back nail. Depending from the under side of the lever D² is the pin f², to which is attached the spring f, with its opposite end secured to the pin f', depending from the arm E, and located

beyond said pin f' is the slot D⁴, which is longer than the pin D³, so as to allow a yielding movement between the lever D² and the arm E. When the top-lift-carrying device is in its outer or receiving position, as shown in Figs. 3 and 4, the coöperating parts shown in Figs. 14 and 15 are in the positions indicated in said figures; but when the top lift moves inward over the heel for attachment the coöperating parts shown in Figs. 16 and 17 are in the positions indicated in those figures. When the block B³ moves downwardly from the position shown in Fig. 5 to that shown in Fig. 6, the top lift is spanked onto the attached heel, and owing to the force of the blow of the spanker-block B³ on the rigid heel of the shoe located on the last the leather of the top lift spreads out, which causes the forward end of the plate F³ to move laterally and yield by means of the spring F⁶, and at the same time the forward end of the plate E⁷ moves laterally and yields by means of the spring f, so that the top lift is not marred by the force of the blow of the spanker-block B³, its spreading being thus provided for as above described.

The plate E⁷ is secured to the boss E⁶, carrying the bifurcated arm E⁴, fast on the shaft E', and through the slot E³ of said bifurcated arm E⁴ passes the depending rod E², fast to the under side of the arm E. By the constructions previously described the plate E⁷ yields as the rod E² moves the arm E slightly toward the right from the position shown in Fig. 17 by the yielding of the spring f, and after the top lift is attached the spring f returns the arm E to the position shown in Fig. 17.

The loaded heels are secured on the heel-block B² by means of the carrying and holding fingers J, which may be of any desired construction and form no part of this invention. When the boy has placed a loaded heel X on the heel-block B² and the same is held there by the fingers J, the boy operates the latch C to release the heel-block and allow it to be turned and brought into the position shown in Fig. 2. During this operation the top-lift-carrying device hereinbefore described moves out of alignment under the spanker-block B³ in the position shown in Figs. 1 and 8 to the position shown in Figs. 2 and 9, when the boy places the top lift Y on the top-lift-carrying device in the manner shown in Fig. 10. In the meantime the operator has placed the shoe A³ on the jack A² and operates the cross-head A to bring down the heel from the position shown in Fig. 2 to that shown in Fig. 4 for attachment to the shoe and then turning the arm B⁴ brings the heel-block B² up into the position shown in Fig. 5. This movement brings the top-lift-carrying device into position over the attached heel and under the spanker-block B³,

Fig. 6, when the operator brings the cross-head A down and spans the top lift onto the attached heel and upon the upward movement of the cross-head A leaves the entire heel Y' secured to the shoe.

When the parts are in the position shown in Fig. 1, the top-lift-carrying device is directly under the spanker-block B³ and over the shoe; but when the boy throws the block B² to bring it around over the shoe in the position shown in Fig. 2 the top-lift-carrying device moves from its horizontal position (shown in Fig. 8) to that shown in Fig. 9, ready to receive the top lift by the movement of the lever D², arm E, rod E², and arm E⁴ to the boss E⁶, to which the top-lift-carrying device is secured. When the operator turns the arm B⁴ to turn the heel-block up and turn the spanker-block down, the top-lift-carrying device, which has received a top lift, moves from the position shown in Fig. 10 to that shown in Fig. 11 through the operation of the lever D², arm E, rod E², and bifurcated arm E⁴, hereinbefore described, when the top lift is in position to be spanked onto the attached heel. The hub B with the blocks B² B³ do not rotate continuously in one direction, but oscillate in an arc of one hundred and eighty degrees.

Having thus described the nature of my invention and set forth a construction embodying the same, what I claim as new, and desire to secure by Letters Patent of the United States, is—

1. In a heel-attaching machine, a jack for the boot or shoe, a cross-head reciprocative relatively to said jack, a spanker-block rotatably mounted on said cross-head and co-operating with said jack, a top-lift-carrying device pivoted to a fixed part of the machine, a pivoted lever movable with said cross-head and having a sliding connection with said top-lift-carrying device, and an arm rotatable with said spanker-block and connected with said lever.

2. In a heel-attaching machine, a jack for the boot or shoe, a cross-head reciprocative relatively to said jack, a spanker-block rotatably mounted on said cross-head and co-operating with said jack, a top-lift-carrying device pivoted to a fixed part of the machine, a pivoted lever movable with said cross-head and having a sliding connection with said top-lift-carrying device, an arm rotatable with said spanker-block, and a yielding connection between said arm and said lever.

3. In a heel-attaching machine, a jack for the boot or shoe, a cross-head reciprocative relatively to said jack, a spanker-block rotatably mounted on said cross-head and co-operating with said jack, a fixed support, a top-lift-carrying device pivoted to said support, a pivoted lever movable on said fixed support in the same direction as said cross-

head and having a sliding connection with 65 said top-lift-carrying device, an arm rotatable with said spanker-block, and a link connecting said arm with said lever.

4. In a heel-attaching machine, a jack for the boot or shoe, a cross-head reciprocative 70 relatively to said jack, a spanker-block rotatably mounted on said cross-head and co-operating with said jack, a fixed support, a top-lift-carrying device pivoted to said fixed support, a pivoted lever movable on said 75 fixed support in the same direction as said cross-head and having a sliding connection with said top-lift-carrying device, and an arm rotatable with said spanker-block and having a yielding connection with said lever. 80

5. In a heel-attaching machine, a jack for the boot or shoe, a cross-head reciprocative relatively to said jack, a spanker-block rotatably mounted on said cross-head and co-operating with said jack, a fixed support, a top-lift-carrying device pivoted to said fixed support, a pivoted lever movable on said 85 fixed support in the same direction as said cross-head and having a sliding connection with said top-lift-carrying device, an arm rotatable with said spanker-block, a link pivoted to said arm and having a loose connection with said lever, and a spring connecting 90 said link with said lever.

6. In a heel-attaching machine, a jack for the boot or shoe, a cross-head reciprocative 95 relatively to said jack, a spanker-block rotatably mounted on said cross-head and co-operating with said jack, a fixed support, a top-lift-carrying device pivoted to said fixed support, a bifurcated arm on said top-lift-carrying device, a pivoted lever movable on 100 said fixed support in the same direction as said cross-head, a rod on said lever registering with said bifurcated arm, and an arm rotatable with said spanker-block and connected with said lever. 105

7. In a heel-attaching machine, a jack for the boot or shoe, a cross-head reciprocative relatively to said jack, a spanker-block rotatably mounted on said cross-head and co-operating with said jack, a fixed support, a top-lift-carrying device pivoted to said fixed support, a bifurcated arm on said top-lift-carrying device, a pivoted lever movable on said 110 fixed support in the same direction as said cross-head, a rod on said lever registering with said bifurcated arm, an arm rotatable with said spanker-block and connected with said lever, a link pivoted to said rotatable arm and having a loose connection with said lever, and a spring connecting said link with said lever. 115

8. In a heel-attaching machine, a jack for the boot or shoe, a cross-head reciprocative 120 relatively to said jack, a hub rotatable on said cross-head, a block on said hub for carrying and attaching a loaded heel, a spanker-

block on said hub, a top-lift-carrying device pivoted to a fixed part of the machine, an arm on said hub, a link pivoted at one end to said arm, a pivoted lever connected with the other end of said link, a bifurcated arm on said top-lift-carrying device, and a rod on said lever and registering with said bifurcated arm.

In testimony whereof I have signed my name to this specification, in the presence of two subscribing witnesses, this 23d day of January, A.D. 1903.

ERASTUS WOODWARD.
